UNITED STATES PATENT OFFICE

STANLEY P. LOVELL, OF NEWTON, MASSACHUSETTS, ASSIGNOR TO ARDEN BOX TOE COMPANY, OF WATERTOWN, MASSACHUSETTS, A CORPORATION OF MASSACHUSETTS

SHOE STIFFENER

No Drawing.

Application filed November 28, 1930. Serial No. 498,759.

The subject of this invention is shoe stiffeners, by which is meant more specifically shoe parts of the character of box toes or counters.

In order to minimize the undesirable effect of the relatively thick and rigid edges of such stiffeners after their incorporation into shoes, it has been the custom to skive the marginal portions of such stiffeners so that they diminish gradually in thickness to a feather edge, which is intended to merge imperceptibly with the shoe upper material. In fine shoemaking, however, especially where upper material such as leather of considerable elasticity is lasted by modern methods conducive to maximum stretching of such upper material, the removal of the last from the shoe is inevitably accompanied by contraction of the upper material, particularly in those areas which lack a backing or support of stiffener material. Thus, contraction of the upper material brings the relatively rigid edge of a stiffener to bear sufficiently against the upper material to raise a prominent ridge therein, which not only detracts from the appearance and salability of the shoe, but whose prominence and hence ungainliness, paradoxically though it may seem, are greater the finer the lasting.

In accordance with the present invention, I do away with the foregoing difficulties by rendering the marginal portions of shoe stiffeners permanently and sufficiently limp so that they yield or recede readily under the contraction of the upper material, rather than raising unsightly ridges therein. I have found that the desired limpness may be imparted to the marginal portions by treating them, preferably after skiving, with an agent which transforms the stiffener material and the fibrous foundation in which it is carried to a permanently limp or plastic condition.

While not limited thereto, I shall now deal more specifically with the application of my invention to three classes of box toes which are used widely in shoemaking. All these classes of box toes have the common feature that they consist of a fibrous foundation, such as felt or other fabric, impregnated with a material which acts to stiffen the foundation markedly. They also have the

common capability of being made temporarily limp by a suitable treatment in order to be conformable to the shape of the last, and of then hardening or stiffening in place in the shoe. One class of box toes contains 55 pyroxylin or celluloid as the stiffening agent. To the skived marginal portions of such stiffeners, I apply plasticizing agents such as dibutyl phthalate, tetraethylene glycol monoethyl ether, tri-ethyl-amine, tri-cresyl-phosphate, ethyl lactate, castor oil, or rape seed oil, which keep the marginal portions permanently limp. The treatment of this class of stiffeners with volatile solvents of the pyroxylin or celluloid type to make the stiffeners temporarily limp does not significantly affect the permanent limpness of the marginal portions, because of the greater affinity of the plasticizing agent for the fibrous foundation than for the volatile solvent. Another class of box toes contains starch, glue, or kindred water-soluble materials as the stiffening agent. I treat the skived marginal portions of such stiffeners with plasticizing agents such as glycerine or tri-ethanol-amine. In such case, too, the plasticizing agents have greater affinity for the fibrous foundation than for the water with which the stiffeners are temporarily softened or rendered limp, so that the treated, skived 70 marginal portions stay limp indefinitely. Still another class of stiffeners are associated with thermoplastic materials such as normally solid waxes and gums. I employ petroleum or other oils in such case as the permanent plasticizers for the skived marginal portions, the oils being retained sufficiently by the fibrous foundation during the usual heat-treatment to which the stiffeners are subjected to preserve the desired limpness of 80 the marginal portions after the main portions have cooled and become stiff in the shoe.

In speaking hereinbefore about the permanent limpness imparted to the marginal portions of shoe stiffeners, I mean a limpness which endures not only throughout the shoemaking operations, including the pulling of the lasts, and the completion of the shoes, but which persists for a sufficiently long pe- 100

riod thereafter that there is no tendency to form ridges in the shoe uppers by reason of rigidity or stiffness in the edges of the stiffeners and the contraction of the upper material thereagainst. My invention has the important advantage that it does away with the past necessity of guarding carefully against inequalities or irregularities occurring in the skiving of the marginal portions of the stiffeners, as freedom from ridges in the shoe upper does not depend as heretofore upon perfect skiving.

The principles of the present invention extend to situations where it is desired to render shoe stiffeners permanently limp in localities other than their marginal areas, although, as has been described in greater detail, they have valuable application in doing away with the undesirable effect heretofore produced on shoe uppers by the marginal portions of shoe stiffeners, especially when shoe manufacturing involves lasting methods conducive to maximum stretching of the shoe upper.

I claim:

- 25 1. A shoe stiffener of substantially uniform thickness throughout and substantially uniformly impregnated with a stiffening agent but having only a localized portion in permanently limp condition.
- 30 2. A shoe stiffener of substantially uniform thickness throughout and substantially uniformly impregnated with a stiffening agent but having only a marginal portion in permanently limp condition.
- 35 3. A shoe stiffener of substantially uniform thickness throughout and substantially uniformly impregnated with a stiffening agent but having only a skived marginal portion in permanently limp condition.
- 40 4. A shoe stiffener of substantially uniform thickness throughout, consisting of a fibrous foundation impregnated substantially uniformly throughout with a stiffening agent but in permanently plasticized condition only at a marginal portion.
- 45 5. A shoe stiffener of substantially uniform thickness throughout consisting of a fibrous foundation skived at a marginal portion and impregnated substantially uniformly throughout with a stiffening agent but in permanently plasticized condition only at said marginal portion.
- 50 6. A box toe consisting of a fibrous foundation impregnated throughout with pyroxylin, said box toe being skived at a marginal portion and containing only at said portion an agent which renders it permanently limp.
- 55 7. A box toe consisting of a fibrous foundation impregnated throughout with a water-soluble stiffening agent, said box toe being skived at a marginal portion and containing only at said portion an agent which renders it permanently limp.
- 60 8. A box toe consisting of a fibrous foundation impregnated throughout with a thermo-

plastic stiffening agent, said box toe being skived at a marginal portion and containing only at said portion an agent which renders it permanently limp.

In testimony whereof I have affixed my signature.

STANLEY P. LOVELL.
